UNITED STATES PATENT OFFICE.

ABRAHAM REIMER, OF STEINBACH, MANITOBA, CANADA.

BAG-HOLDER.

1,024,360.

Specification of Letters Patent.

Patented Apr. 23, 1912.

Application filed February 27, 1911. Serial No. 611,075.

To all whom it may concern:

Be it known that I, ABRAHAM REIMER, of the village of Steinbach, in the Province of Manitoba, Canada, have invented certain new and useful Improvements in Bag-Holders, of which the following is the specification.

My invention relates to bag holders, and the object of the invention is to provide a simply constructed, durable and easily operated holder which will effectively hold a bag with the mouth thereof properly open for filling purposes when desired, such device being easily manipulated and adjustable to various heights and kinds of bags.

It consists essentially in a set of legs suitably reinforced, telescoping members carried by the legs, swingable gripping devices supported by the said legs and a lever for swinging the gripping devices, the parts being arranged and constructed as herein-after more particularly described and claimed.

Figure 1 is a front elevation of the bag holder in the position ready to receive a bag. Fig. 2 is a plan view of the device in the position shown in Fig. 1. Fig. 3 is a plan view of the bag holder with the parts in the position which they occupy when supporting the bag, a modified form of bag grip being employed. Fig. 4 is a plan view of one of the grips. Fig. 5 is a detail view showing rod 13 as it appears in side elevation.

In the drawing like characters of reference indicate corresponding parts in each figure.

1 and 2 represent two tubular legs having their lower ends forked and supplied with rollers 3. The legs are united by a straight bar 4 and an arched brace 5 and are supplied at their upper ends with adjusting nuts 6 and 7.

8 is a stout metal rod having its ends telescoped within the legs 1 and 2 and the body portion thereof bent at 9 into the form of an open-sided rectangle, such rod being looped at 10 and 11 at the sides of the rectangular portion to form gripping members. The rod 8 forms what I term an adjustable supporting member and it carries the arms 12 and 13, which arms are pivotally secured to the rods 8 at 14, 14' and 15, 15' at the top and bottom respectively and are also looped

at 16 and 17 to form further gripping members. The loops 10, 11, 16 and 17 extend in the horizontal plane and when the holder is in use the bag is placed thereon with the band thereof resting on the loops so that the end is held well open. Bars 18 and 19 extend rearwardly from the said arms and are connected through links 20 and 21 with the enlarged end of a lever 22, the lever being mounted on a stub shaft 23 passing backwardly from the brace 24 and unites the lower horizontally disposed portion of the rod 8 with a cross rod 25 which closes the open side of the rectangular portion 9 hereinbefore referred to. It is to be noticed that the links are connected to the lever at points 70 at the opposite sides of the shaft 23 so that the arms are swung outwardly when the lever is turned in the left hand direction as indicated by the arrow Fig. 1. The links 20 and 21 are each provided with a turn 75 buckle 21' so that the length of the link can be adjusted. A weight 26 is secured to the lever.

As soon as the bag has been placed with the hand over the loops as already described, 80 the lever is swung to the position shown in Fig. 3 of the drawing, with the result that the arms spread outwardly and tighten on the bag. The weight holds the arm in the latter position while the bag is being filled 85 with grain or other such produce. The bag is released from the holder by swinging the arm back to the original position.

The bag holder as above described will hold tightly all bags supplied with bands 90 at their open end, but difficulty might be experienced in supporting a large bag without a band, and for this purpose I have constructed the jaws 27 shown in detail in Fig. 4 and applied to the holder in Fig. 3 of the 95 drawing. These jaws are formed with a roughened or toothed face 28 and are supplied with adjusting screws 29 whereby they can be fastened to the arm and to the rod 8, respectively, directly above the lips or loops 100 10, 11, 16 and 17, when a bandless bag is to be filled. The rough faces of the jaws will grip and hold any bag tightly once the lever is swung over.

If one desires, the jaws could be placed 105 on the bag holder in the first instance, that is, when it is manufactured, and the lips entirely dispensed with. I have shown the

loop construction as it is a very cheap one and the holder so formed will accommodate by far the greater majority of bags.

What I claim as my invention is:

- 5 1. The combination with an adjustable supporting member, of a set of similar arms pivotally secured to the supporting member and swingable toward and away from each other, gripping members carried by the arms
- 10 and by the supporting member, such latter gripping members being located in a higher horizontal plane than the former, bars extending rearwardly from the arms, a pivotally mounted lever carried by the supporting member, links connecting the lever with the respective bars, and an adjustable weight carried by the lever, as and for the purpose specified.
- 15 2. A bag holder comprising a set of similar opposing legs suitably interconnected at

the bottom, an adjustable supporting member carried by the legs and telescoping into the upper ends thereof, opposing arms pivotally secured to the supporting member and swingable toward and away from each other, removable gripping jaws secured to the arms and to the supporting member in pairs, bars extending rearwardly from the arms, a stub shaft located centrally of the supporting member, a lever pivoted on the stub shaft, links connecting the lever with the extending ends of the arms, and a weight adjustably secured to the lever, as and for the purpose specified.

Signed at Steinbach, in the Province of Manitoba, this 29th day of December, 1910.
